UNITED STATES PATENT OFFICE.

WILLIAM P. WATSON, OF MIDDLETOWN, CONNECTICUT, ASSIGNOR OF ONE-THIRD TO PETER B. WATSON, OF COLUMBIA, PENNSYLVANIA, AND ONE-THIRD TO EUGENE H. BURCKHARDT, OF NEW YORK, N. Y.

ATTACHMENT FOR LOOMS.

No. 926,447.

Specification of Letters Patent.

Patented June 29, 1909.

Application filed June 25, 1908. Serial No. 440,257.

To all whom it may concern:

Be it known that I, WILLIAM P. WATSON, a citizen of the United States, and a resident of Middletown, in the county of Middlesex 5 and State of Connecticut, have invented a new and Improved Attachment for Looms, of which the following is a full, clear, and exact description.

This invention has in view a suitable mechanism in connection with a loom, for raising and lowering the weights used to maintain a tension on the warp. At frequent intervals in the operation of a loom, it is necessary for the tension to be removed from the warp in 10 order to rip out an imperfect pick in the cloth. If the tension weights be removed from their cables instead of raising them in releasing the warp, it will be impossible to bring the warp back in precisely the same 15 position after reapplying the weights, and a defective piece of cloth will result. The lifting of the tension weights of looms has heretofore been invariably performed directly by hand, and as they are of considerable weight, 20 added to the fact that looms are operated largely if not exclusively by females, the successful operation of the loom involves an inhuman tax on the endurance. With my invention both weights are simultaneously 25 raised and lowered by mechanical means preferably operable from the front of the machine, which means permits of a heavier weighting and consequently the lengthening of the warp and an increase in production.

Reference is to be had to the accompanying drawings forming a part of this specification, in which similar characters of reference indicate corresponding parts in all the views.

Figure 1 is a partial side elevation of a 40 loom having my improvement applied thereto; Fig. 2 is a rear end elevation of the same; and Fig. 3 is a cross-section on the line 3—3 of Fig. 2, looking in the direction of the arrows.

In the drawings, 5 represents the frame of a well-known type of loom, having arms 6 extended at the rear, which are reinforced by curved brackets or supports 7, and provided with alining longitudinal slots 8. In these 45 slots are adjustably secured hangers 9 which are extended above their connections with the arms, where they are provided with forked or other suitable bearings for the warp beam 10. To the opposite ends of the warp 50 beam are fixed the customary friction wheels,

around which are passed one or more times cables 11, having the tension weights 12, which normally rest on the floor, attached to one end, and the normally suspended weights 12^a secured to their opposite ends, drawing 60 the cables tight about their respective friction wheels.

It is my purpose to provide mechanical means for raising the weights 12, as when it is desired to remove the tension from the 65 warp in ripping out an imperfect pick. In accomplishing this I journal a hollow shaft 13, such as a pipe, on the lower ends of the arms 9, and provide the shaft with longitudinal slots 14 arranged at opposite sides. In 70 these slots are placed buttons or other enlargements 15, attached to the extremities of chains or other flexible members 16, the said chains being provided at their outer and opposite ends with rings or other equivalent 75 members 17, for attaching them to the hooks of the weight hangers, this construction permitting of the adjustment of the chains longitudinally of the shaft to bring them in alinement with the weights. At one side of 80 the machine the shaft 13 is extended directly or by a separate member, to which is attached a bevel gear 18, in mesh with a similar gear 19 secured to a shaft 20, which shaft is arranged at the side of the machine and 85 journaled in bearings 21, preferably of adjustable nature, and respectively carried by the adjacent bracket 7 and the forward portion of the machine frame. To the forward end of the shaft 20, at the front of the machine, is secured a ratchet wheel 22, at the outside of which is journaled on the shaft 20 a hand lever 23, which, as best shown in Fig. 2, is provided with a pawl 24, normally 90 forced into engagement with the ratchet wheel by a spring 25. The ratchet wheel is further engaged by a pawl 26, pivotally supported on a fixed part of the machine and operatively held to the ratchet wheel by a 95 spring 27.

When it is desired to raise the weights 12 on a loom supplied with my attachment, the operator without moving from his or her position, reciprocates the hand lever 23 until 100 the weights are raised to give sufficient slack on the warp. After the pick or other repair has been made, the weights are returned by advancing the ratchet wheel sufficiently to 105 release the pawl 26. This manner of raising and lowering the weights, obviously requires 110

infinitely less physical exertion than is entailed in directly lifting the tension weights from the floor by hand.

Having thus described my invention, I claim as new and desire to secure by Letters Patent:

1. In a loom, means for maintaining a tension on the warp, having weights applied thereto, a hollow slotted shaft journaled 10 above the normal position of the weights, flexible members connected to the weights and having slid able connections through the slots of the shaft, and means for revolving the shaft.
- 15 2. In a loom, means having weights for maintaining a tension on the warp, a shaft journaled on the loom at the rear thereof, flexible devices connected to the shaft and to certain of the weights, a shaft journaled at 20 the side of the loom and operatively connected to the first mentioned shaft, means at the front of the loom to revolve the last-named shaft to wind and unwind the flexible devices on and from the shaft at the rear of 25 the loom, whereby the said certain weights are raised and lowered, and means to lock the shaft at the side of the loom to support the said certain weights at an elevation.

3. In a loom, the combination of a warp beam having friction wheels at opposite ends, 30 cables passing over the friction wheels, each having weights suspended from opposite ends, a shaft, flexible devices between the shaft and weights at corresponding ends of the cables, and means to revolve the shaft to 35 wind and unwind the said devices thereon and therefrom to raise and lower the weights.

4. In a loom, means for maintaining a tension on the warp, having weights, a shaft at the rear of the loom, flexible connections 40 between the weights and the shaft, a shaft at the side of the loom, operatively connected with the first mentioned shaft, a ratchet wheel fixed to the last mentioned shaft at the front of the loom, a hand lever having a pawl 45 normally engaged with the ratchet wheel, and a pawl carried by a fixed part of the loom, in operative engagement with said wheel.

In testimony whereof I have signed my 50 name to this specification in the presence of two subscribing witnesses.

WILLIAM P. WATSON.
